Primary Examiner — Marianne Pandozzi(74) *Attorney, Agent, or Firm* — Loeb & Loeb LLP(57) **CLAIM**

The ornamental design for a carafe, as shown and described.

DESCRIPTION

FIG. 1 is a perspective view of an embodiment of a carafe showing my new design.

FIG. 2 is a left side elevational view of the carafe of FIG. 1.

FIG. 3 is a right side elevational view of the carafe of FIG. 1.

FIG. 4 is a front elevational view of the carafe of FIG. 1; and,

FIG. 5 is a top plan view of the carafe of FIG. 1.

The broken lines in the drawings are included for the purpose of illustrating environmental structure and form no part of the claimed design.
